CLAIM

We claim the ornamental design for an airport for vertical take-off and landing aircraft, as shown and described.

DESCRIPTION

FIG. 1 is a rear perspective view of an airport for vertical take-off and landing aircraft showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings represent unclaimed environmental structure in the form of an aircraft, as well as illustrating portions of an airport for vertical take-off and landing that form no part of the claimed design.
